UNITED STATES PATENT OFFICE

2,560,453

HEAT EXCHANGE UNIT FOR
REFRIGERATIONHerman W. Kleist, Chicago, Ill., assignor to Dole
Refrigerating Company, Chicago, Ill., a corpo-
ration of Illinois

Application February 9, 1946, Serial No. 646,558

3 Claims. (Cl. 62—129)

1

This invention relates to heat exchange devices or units, and has for one purpose to provide a heat exchange or refrigerating unit particularly adapted for cooling a current or circulation of a fluid or gas, such as air.

Another purpose is to provide a heat exchange unit which may be partly or wholly preassembled and which, when preassembled, includes a plurality of parallel plane faced plates and means for securing them in relation to each other at a proper distance to permit the passage through the plates of the liquid or gas being cooled.

Another purpose is to provide an efficient heat exchange means utilizable in refrigeration and for example, in refrigerating cars.

Another purpose is to provide a unit which may be advantageously used in connection with air conditioning.

Another purpose is to provide a unit with which fluid moving means, such as a fan, may be directly associated.

Another purpose is to provide a unit of refrigerating plates in which there is a minimum tendency for the formation of frost, and in which the circulated medium to be cooled, which flows between the plates, is effective to reduce the retention of frost on the plate surfaces.

Another purpose is to provide a battery of plane faced refrigerating plates, secured together in suitable spaced relationship, and adapted for installation as a unit.

Other purposes will appear from time to time in the course of the specification and claims.

The present application is a continuation in part of my co-pending application Serial No. 482,097, filed in the U. S. Patent Office on April 7, 1943, which issued on November 5, 1946 as Patent No. 2,410,449, for refrigerator cars.

I illustrate the invention more or less diagrammatically in the attached drawings wherein:

Figure 1 is a vertical section illustrating my invention as applied to a system of air ducts which may be employed, for example, in refrigerating the interior of a freight car, section being taken on the line 1—1 of Figure 2;

Figure 2 is a section on the line 2—2 of Figure 1;

Figure 3 is an interrupted section on the staggered line 3—3 of Figure 1;

2

Figure 4 is a section on the line 4—4 of Figure 3;

Figure 5 is a section on the line 5—5 of Figure 3;

5 Figure 6 is a diagrammatic illustration of the entire system;

Figure 7 is a perspective view of a variant form of my invention; and

10 Figure 8 is a section on the line 8—8 of Figure 7.

Like symbols refer to like parts throughout the specification and drawings.

The present drawings of Figures 1 to 6 are identical with Figures 4 to 9 inclusive of said co-pending application Serial No. 482,097, in which my invention was applied to the refrigeration of a freight car. Since the freight car as such does not form part of the present invention, its details have been omitted from the present drawings.

15 It will be understood, however, that I may employ any suitable system of ducts, including duct 1, effective to supply the air or fluid to be cooled. 2 indicates any suitable housing in which the heat exchange member is positioned.

20 The housing may have a cool air outlet 3 through which the air or other medium to be treated may pass after the desired heat exchange has taken place. The heat exchange unit proper is shown as enclosing between upper and lower inclined walls 8 and 9, the side walls 7 being effective to complete the closure of the space.

25 Mounted within this enclosing device are a series of cooling elements which are preferably plates, each made up of two sheets 11 and 12 of heat conducting material with a space between them in which the refrigerant material is located so as to cool the plates. These plates have smooth exterior surfaces. I prefer to use vacuum

30 plates each with a pipe 13 coiled back and forth in the space between the sheets, shown in detail in Figures 3, 4 and 5. These sheets are connected together with a hermetically sealed connection so as to be airtight. Each sheet 11 is provided with a bent-over edge 14 which has a sealed

35 connection to the sheet 12, and each sheet 12 has a projecting part 15 which projects outwardly from the bent portion 14 at least at two opposite extremities although it may project outwardly all the way around the sheet. The bent

40 over edge 14 may be hermetically fastened to the

45

sheet 12 in any desired manner, as by welding 16. Means are provided for withdrawing air from the interior of the plates 10. One arrangement for this purpose is shown in Figure 5 wherein there is a plug 17 which projects through an opening in the bent-over portion 14 and which is provided with an opening extending all the way through, the opening being arranged in two sections, a section 18 of comparatively small diameter and a section 19 of larger diameter. There is a valve 20 in the section 19. An air withdrawing device is attached to the portion of the plug projecting from the plate and the desired amount of air is withdrawn. During this process the valve 20 moves away from its seat 21. When the withdrawal of air ceases this valve is moved onto its seat by the pressure of exterior air. A closing member 22 is then inserted into the plug and may be sealed by welding or soldering or in any other desired manner. The plates may preferably contain a suitable eutectic 23 so as to make them hold-over plates. This eutectic does not completely fill the plates as a space is left from which air is withdrawn and which permits the eutectic to expand when frozen. The withdrawing of air from the space between the sheets of the plates causes the outside atmosphere to tightly press the sheets against the pipe 13 so as to secure a tight heat exchange contact between the sheets 11 and 12 and the pipe 13. When the hold-over plate is used this eutectic is frozen and acts as a cooling agent for a considerable time after the refrigerant material has ceased to flow through the pipe 13. The plates 10 may be supported and arranged in the enclosing device at the end of the car in any suitable manner. These plates may be arranged in a horizontal or vertical position and may be parallel to the roof of the car or inclined with relation thereto.

In Figures 1 to 4 I have shown one particular way of arranging and supporting these plates 10. In this construction the plates are shown with their flat faces extending in a generally horizontal direction, the plates, however, being inclined with their edges nearest the cool air outlet higher at their opposite edges. There are a series of supporting members 24 which are provided with a series of notches 25. The projecting edges 15 of the plates fit into these notches, as clearly shown in Figure 4. Fastening devices 26 pass through the supporting devices 24 and bind them together so as to hold the plates rigidly in position. These fastening devices 26 pass through the supporting devices 24 and bind them together so as to hold the plates rigidly in position. These fastening devices may be of any suitable form, and as herein shown consist of rods threaded at their ends with nuts 27 on the threaded ends which are tightened up to bind the plates in position.

The supporting devices are fastened to the fastening members 28 by means of the threaded rods 26 and nuts 27. The fastening members 28 at one end of the set of plates are fastened in position by the bolts 29 and the nuts 30. Fastening members 28 at the opposite end are secured by bolts 30 to the angle supports 31 connected with the ceiling 62 of the car. Associated with the plates 10 are one or more air-moving devices 31. These air-moving devices are placed in front of the plates, and instead of forcing the air between the plates, they draw the air through such plates. These air-moving devices are actuated by the motors 32, suitably mounted in position

upon the supports 33 and 34, which are attached to the frame 35. There is preferably a screen 36 in front of the air-moving devices 31, through which the air is passed. The present arrangement may advantageously be used in cooling freight cars or rooms of substantial content, with the unit located adjacent the ceiling, or having a cool air discharge outlet adjacent the ceiling. The air is cooled by being drawn in between these several plates and in contact therewith, and is then forced outwardly and into contact with the ceiling and thus is distributed throughout the car. The fact that the plates 10 are inclined, as shown in Figure 1, assists greatly in having this air move upwardly into contact with the ceiling. Some suitable means is provided for supplying the plates 10 with a suitable refrigerant and passing it through the coils 13. As herein shown, there is a refrigerating apparatus provided with the compressor 37, with some suitable motor for operating it, such as the motor 38, which may be a Diesel engine. Compressor 37 is connected with the condenser 39 and the receiver 40.

A connection 41 leads from the receiver 40 to a heat exchanger 42 (see Figure 6). This heat exchanger is connected by a pipe 43 with a strainer 44. The strainer is connected by a pipe 45 with an expansion valve 46. A series of pipes 47 connect the expansion valve with the several plates 10, and by this means a more uniform temperature is secured in all of the plates. The refrigerant then passes through the coils in these plates and passes out of the plates through the connections 48 to the common pipe or header 49. This header is connected by a pipe 50 with the heat exchanger 42 (see Figure 6). A pipe 51 leads from the heat exchanger back to the compressor. Connected with the pipe 51 is a T 52 in which is located a bulb 53. This bulb controls, that is, opens and closes, the expansion valve by the usual means consisting of the pipe 54. When the refrigerant returning from the plates 10 rises above a certain temperature, this bulb causes the expansion valve to open and admit the refrigerant to the coils in the plates 10, and when the temperature of this refrigerant falls below a certain predetermined temperature, the bulb causes the expansion valve to close and shut off the refrigerant from the coils in the plates 10. It will thus be seen that the temperature in the room is automatically controlled.

As before stated, the cooled air is preferably thrown up against the ceiling and is then deflected and distributed throughout the room. The air-moving devices may be arranged at different angles so as to cause the cooled air to strike the ceiling of the room at different points therealong and be deflected to secure a more uniform cooling throughout the room. This cooled air, after absorbing heat from the articles to be cooled in the room, passes into the duct 1 and the suction of the air-moving devices moves this air up through the passageway 1 and again into contact with the plates 10 where it is cooled and sent back into the room.

At 42 in Figure 6, I illustrate any suitable heat exchanger including an outer housing 42 surrounding the refrigerant coil 58. The refrigerant passing through the pipe 41 passes through the coil 58 within the heat exchanger casing 42, and thence to the strainer. The refrigerant returning from the header 49 passes through the casing 42 in contact with the exterior of the coil 58, so that there is a transfer of heat between the

refrigerant in the coil 58 and the refrigerant on the exterior of the coil.

The motor, compressor and condenser may be located in any desired point. I prefer, however, to have them located in a casing connected to the exterior of the bottom of the car.

The frame 35 upon which the motor 32 and the fan 31 are mounted is preferably hinged as shown in Figure 1, so that it can be moved to expose the motor and fan for inspection and repair. If desired, the pin of the hinge may be removed so that the entire member 35, together with the motor and the fan, may be removed to the shop for repair or replaced by a new one.

With reference to the form of Figures 7 and 8, I illustrate a group or battery of cold plates which are the same in detail and in supporting means as the group of plates illustrated in Figure 1. Therefore, the same indicating symbols are employed. However, the plates shown in section in Figure 8 are arranged within a housing 63. As will be clear from Figure 7, the housing is substantially higher than the height of the group of plates, providing a top plenum chamber from which air may be exhausted through the side wall aperture 64, aligned with the fan 31 and the fan motor 32. The lower end of the housing 63 may be provided with any suitable air inlet, or may be left open. In either event, it is preferably upwardly spaced from the floor or supporting surface, for example, by the legs or supports 65. It will be clear from Figure 8 that the plates 10, taken in conjunction with the housing 63 and the housing end walls 66, defining a series of flat, parallel, shallow air cooling passages through which air is simultaneously moved, and in the same direction. As a matter of convenience, I illustrate the fan 31 as withdrawing cold air from the plenum chamber. However, the fan can be placed at any other convenient location, or any other suitable means may be employed for causing the air undergoing cooling to flow between the plates 10.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of my invention are as follows. When the parts are assembled and it is desired to cool the interior of the room, the motor is set in operation and the refrigerant is forced by the compressor 37 through the condenser 39, receiver 40, pipe 41 and through the coil 58 in the heat exchanger 42 to the strainer 44, and thence into the expansion valve 46. The refrigerant then passes through the several pipes 47 from the expansion valve to the coils in the different plates 10, wherein it cools the air in contact with the plates. The refrigerant then passes out of the pipe 48 into the header 49, and thence by pipe 50 through the casing of the heat exchanger 42 in contact with the coil therein, and thence by pipe 51 back to the compressor. This causes the plates 10 to be cooled and the air-moving devices 31 actuated by the motors 32 draw the air through the spaces between the plates 10. This air is cooled by the plates and the cooled air is then directed into the interior of the room. This cooled air is distributed

throughout the interior of the room and absorbs heat from the material therein which is to be cooled, and eventually returns through the passageway 1 to contact again the plates 10.

I have shown one means of controlling the temperature in the room by means of the bulb 53 and the expansion valve 46. When a Diesel engine, for example, is used, the temperature may be controlled by starting and stopping the Diesel engine automatically responsive to the temperature in the interior of the room. Any of the Diesel engine automatic control means produced by any of the Diesel engine companies may be used for this purpose. With such a controlling device the temperature controlled element is placed at a suitable position, and when the temperature in the room falls below a predetermined point the engine is automatically shut off, and when the temperature in the room rises above a predetermined point, the engine is automatically started. It is, of course, evident that an electric motor or any other form of motor may be used. The particular type or form of motor may be changed or altered to suit the conditions presented.

In the form of Figures 7 and 8, I illustrate a unit which may be used to cool any room or space, and which takes the air to be cooled directly from the bottom of the space, cools it, and returns it to the space at a higher level. However, it will be realized that I may employ any suitable duct system or combination air ducts, the essential feature of my invention being the employment of parallel plane surfaced cooling members which define preferably shallow passages of generally uniform thickness between plates, with a substantial elimination of eddy currents.

I claim:

- 40 1. In a heat exchange unit, an air directing housing having an inlet at one end and an outlet at the other, a plurality of plates in said housing, each said plate having a smooth, plane unrestricted face at each side thereof, said plates being parallel and being separated by relatively restricted spaces defining air passages of uniform thickness substantially from edge to edge of the plates, a source of refrigerant supply, a connection therefrom to said plates, a return connection 45 from the plates to the refrigerant supply, the connection to said plates including a pressure reducing device and parallel connections therefrom to said plates.
- 45 2. In a heat exchange unit adapted for cooling spaces such as refrigerator car interiors, a plurality of refrigerating plates and means for passing a volatile refrigerant therethrough, each plate having opposite, generally parallel plane, unbroken faces, means for supporting said plates 50 in generally parallel planes in spaced relationship, with the plane faces of adjacent plates separated by relatively shallow, unbroken air conduit spaces, with substantially uniform clearance from edge to edge of the plates, and housing means 55 adapted to close the opposite sides of said air conduit spaces, the means for passing the refrigerant through the plates including an expansion valve and parallel, individual connections from said expansion valve to a plurality of plates.
- 60 3. In a heat exchange unit adapted for cooling spaces such as refrigerator car interiors, a plurality of refrigerating plates and means for passing a volatile refrigerant therethrough, each plate having opposite, generally parallel plane, unbroken faces, means for supporting said plates 65
- 65
- 70
- 75

in generally parallel planes separated by relatively shallow, unbroken air conduit spaces, with substantially uniform clearance from edge to edge of the plates, and housing means adapted to close the opposite sides of said air conduit spaces, the means for passing the refrigerant through the plates including an expansion valve and parallel, individual connections from said expansion valve to a plurality of plates and a return manifold to which the plates are connected in parallel.

HERMAN W. KLEIST.
